UNITED STATES PATENT OFFICE.

JOHN C. BUNTIN, OF MITCHELLVILLE, TENNESSEE.

DESIGN FOR A STIRRUP.

SPECIFICATION forming part of Design No. 29,416, dated September 27, 1898.

Application filed February 28, 1898. Serial No. 672,104. Term of patent 7 years.

To all whom it may concern:

Be it known that I, JOHN C. BUNTIN, a citizen of the United States, residing at Mitchellville, in the county of Sumner and State of Tennessee, have invented or produced a new and original Design for Stirrups, of which the following is a specification.

The object of my design is to provide a novel, ornamental, and handsome stirrup for riding-saddles which presents a characteristic and peculiar appearance to the eye; and the leading feature of the design consists in a stirrup composed of an endless polygonally-shaped band having its manifold sides rectilinear, as hereinafter explained in detail.

The design is illustrated by the accompanying drawings, in which—

Figure 1 is a perspective view of my new and original design for a stirrup, and Fig. 2 is a central vertical sectional view of the same.

In the accompanying drawings the numerals 1, 2, 3, 4, 5, 6, 7, and 8 indicate the manifold rectilinear sides of the stirrup, which is in the form of an endless polygonally-shaped band. This band, as shown, is uniform in

width, and the uppermost rectilinear side 8, which is the top of the stirrup, is somewhat shorter than the other rectilinear sides and contains a transverse eye or slot 9. The rectilinear sides 1 to 7, inclusive, are coequal in length and their opposite edges are beveled or rounded, as at 10, to give the parts a finished and nice appearance. The edges of the rectilinear side 8 are rounded or convex in shape, as at 12.

A stirrup made according to my design is handsome and ornamental and possesses a characteristic appearance which distinguishes it from prior articles of the kind.

What I claim is—

The design for a stirrup, substantially as shown and described.

In testimony whereof I have hereunto set my hand in presence of two subscribing witnesses.

JOHN C. BUNTIN.
